J. H. ENRIGHT

PUZZLE

Filed Jan. 30, 1923

INVENTOR.

JOHN H. ENRIGHT

BY

Joseph J. O'Brien

ATTORNEY.

UNITED STATES PATENT OFFICE.

JOHN H. ENRIGHT, OF PITTSFIELD, MASSACHUSETTS.

PUZZLE.

Application filed January 30, 1923. Serial No. 615,805.

To all whom it may concern:

Be it known that JOHN H. ENRIGHT, citizen of the United States of America, residing at 173 North St., Pittsfield, in the county of Berkshire and State of Massachusetts, has invented certain new and useful Improvements in Puzzles, of which the following is a specification.

This invention relates to improvements 10 in puzzles and its leading object is to provide a puzzle of simple construction comprising a series of separated receptacles arranged in a common container or enclosure and a series of balls, the receptacles having 15 distinctive colors or numbers or the like and the balls being arranged in groups or pairs, certain of the groups or pairs having a color or number corresponding to one of the receptacles, which is so arranged that the balls 20 can be rolled into the receptacles so that the color or numbers of the balls will be located in the receptacle corresponding thereto.

With the above and other objects in view, the invention relates to certain new and useful 25 constructions, combinations and arrangements of parts, clearly described in the following specification and fully illustrated in the accompanying drawings, in which:

Fig. 1 is a plan view.

Fig. 2 is a transverse sectional view.

Referring to the accompanying drawings, 5 designates a container or enclosure having a base 6, side walls 7 and 8, and an end wall 9, all arranged to provide a box-like enclosure. The container is provided with a glass or transparent cover or top wall 10. In each corner of the enclosure or container is constructed a receptacle in the form of an L-shaped wall, four receptacles being 10 shown in the four corners of the rectangular container or enclosure. The receptacles or pockets have end walls 12 provided with openings 13 therein. The openings of the receptacles on each side of the container are 15 arranged in opposition to each other and the upper marginal edge of the openings is located below the transparent cover 10 so as to provide a ridge 13 which is adapted to form a stop when the device is inverted.

Any system or color designation may be 20 used, but the one preferred by me includes the colors red, white, green and blue and these colors may be numbered 1, 2, 3 and 4 or

lettered *a*, *b*, *c* and *d*, or any other system of symbols may be used. In this way each 65 receptacle is provided with its own individual, distinctive symbol or number. The receptacles are spaced from each other to provide a cruciform run-way 14 which is as wide as the space between the sides of the 70 receptacles and the confronting ends thereof.

A series of rollable articles or balls 15 are arranged to roll or move in the runway and into and out of the separate receptacles. These balls are preferably arranged in 75 groups or pairs and each pair or group is provided with a color or symbol, or distinctive identifying mark corresponding to that of one of the receptacles, so that one group will have a red color, another a white, 80 a third a green color and a fourth a blue color, if this color combination is employed, and other colors if a different combination is employed.

The object of the puzzle is to locate the 75 balls or objects of each of the colors or markings or designations, in the receptacle having a corresponding color, marking or designation, so that the colors or markings of the objects will be located in the receptacle of a corresponding color or marking, at the one time. The receptacles are so arranged that the entrance openings through which the balls or objects enter and leave the receptacles are smaller than the receptacles themselves and are arranged directly 85 opposite each other so that when an effort is made to locate the red balls in the red receptacle, the balls in the other receptacles will have to be held from rolling from their 90 positions and the effort of the puzzle largely consists in imparting momentum to certain 95 of the balls while holding others against rapid movement. The puzzle provides a great deal of amusement, entertainment and even excitement to young and old persons. Perfectly spherical balls may be used or balls having a somewhat irregular surface 100 may be used so that their rolling action can not be accurately guided and the difficulty of matching the balls somewhat increased.

Having described my invention, I claim.

A puzzle consisting of a box having a receptacle in each corner thereof, the receptacles being spaced from each other to provide a cruciform runway between the re- 105

ceptacles, each of the receptacles having an opening in one end thereof of less width than the width of the receptacle, the openings of one part of the receptacles confronting the openings of the other part of the receptacles in substantially parallel lines, and a series of rollable articles arranged in

the box, movable into each of the receptacle openings, said articles being arranged in groups, having definite characteristics, ¹⁰ the puzzle being designed to permit of one group being positioned in each receptacle.

Signed by me at Pittsfield, Mass.

JOHN H. ENRIGHT.
